UNITED STATES PATENT OFFICE.

PRUDENCE ANN SMITH, OF PINE HILL, NEW YORK.

DRESS-FORM.

No. 839,431.

Specification of Letters Patent.

Patented Dec. 25, 1906.

Application filed March 2, 1906. Serial No. 303,921.

To all whom it may concern:

Be it known that I, PRUDENCE ANN SMITH, residing at Pine Hill, in the county of Ulster and State of New York, have invented certain new and useful Improvements in Dress-Forms, of which the following is a full, clear, and exact description, such as will enable others skilled in the art to which it appertains to make and use the same.

This invention relates to dress-forms; and one of its objects is to provide a device of the above character which will be simple and durable in construction and capable of being quickly changed or adjusted to different-sized forms, according to the size and shape of person for whom garments are being made.

Another object is to provide in an inflated or pneumatic dress-form means whereby the same may be made to correspond exactly with the contour of a human figure.

A further object is to so construct the form that the several parts of which it is comprised may be disconnected from one another and stored or packed to occupy little space when not in use.

Other objects will be in part obvious and in part pointed out hereinafter.

The invention accordingly consists in the features of construction, combinations of elements, and arrangement of parts which will be exemplified in the device hereinafter described and the scope of the application of which will be indicated in the following claims.

In the accompanying drawings, wherein are illustrated two of the various possible embodiments of my invention, Figure 1 is a view in perspective showing one of the embodiments thereof in an inflated condition. Fig. 2 is a similar view of the inner inflated form. Fig. 3 is a vertical sectional view taken through Fig. 1. Fig. 4 is a view in perspective of a slightly-different embodiment thereof. Fig. 5 is a view showing the form and its supporting parts collapsed and stored within the hollow base portion. Fig. 6 is a sectional view of the embodiment illustrated in Figs. 1, 2, and 3, taken on line 6-6 of Fig. 2.

Similar reference characters refer to similar parts throughout the several views of the drawings.

In the use of pneumatic dress-forms as heretofore constructed difficulties have arisen by reason of the fact that the forms when inflated cannot be made to correspond exactly

to all of the transverse measurements of a human form, and in eliminating these difficulties I have found it desirable to provide mechanical means adapted to connect or tie together opposite walls of the inflated form, so that certain parts or areas thereof may be positively retained against bulging under the pressure of inflation. I have also made the means for connecting the walls of the casing adjustable, whereby said connected parts or areas may be depressed to different degrees according to the transverse dimensions of a human figure.

It will be apparent from the following description of the embodiments I have selected to illustrate my invention that I obtain the above and other advantages through the provision of a simple and efficient device and, moreover, one which can be readily collapsed in small space for storage or transportation.

Referring now to the drawings and particularly to the embodiment shown in Figs. 1, 2, 3, and 6, there is shown at 1 an inflatable bag, herein designated "form," which may be made of flexible, elastic, or non-elastic material and conforming when inflated approximately to the shape of the body portion of a human figure. Form 1 is mounted upon a base portion 2 and is provided with a tube 3, by means of which it may be inflated with air, either by the operator blowing into the same or by means of a suitable air-pump connected therewith. A check-valve 4 is provided in tube 3. Extending transversely through form 1 are apertures 6 and 7. As shown herein, one of these apertures is provided slightly above the bust portion and one near each of the shoulder portions.

Upon form 1 when in a deflated or collapsed condition is placed one of a series of different-sized covers or casings 8, constructed of a relatively inelastic material and made according to measurements taken from the person for whom the garment is intended, preferably by fitting the casing directly to said person, said casing being adapted to be flexibly connected with base portion 2 by means of a plurality of cords or tapes 9, which may be attached to buttons 10 or to other suitable devices extending from said casing.

As will be readily understood, when form 1 is inflated by pumping or blowing air into the same casing 8 will be distended to produce a form according to which the garment may be

made or fitted. It has been found, however, that owing to the pressure of inflation certain parts or areas of casing 8 have a tendency to expand or bulge slightly, and to remedy this defect I have provided a plurality of tapes, as at 11, Fig. 3, said tapes being secured to one wall and extending transversely thereof through openings 6 and 7 of form 1 and connected with suitable devices, as eyes, secured to the opposite wall of said casing. Tapes 11 are of flexible but relatively inelastic material and correspond exactly in length to the corresponding transverse dimensions of the person for whom the garment is to be constructed.

While the connecting means employed in the above relation are shown as tapes, cords may, as will be apparent, be used, and by the term "tapes," as used herein, I intend to include any flexible relatively inelastic member capable of being employed in this relation.

Although the connecting-tapes could be employed with equal facility as connecting means for any portion of the walls of the casing, it has been found in practice that the parts of the casing most liable to expand or bulge are those above the bust portion and near the shoulder portion, and it is those parts that I have connected by means of the tapes 11.

In the embodiment illustrated in Fig. 4 I provide form 1 with a permanent envelop or covering 12, secured to base portion 2, said covering being of a size slightly less than that to which form 1 will ever be inflated. It will be understood, of course, that covering 12 in use is interposed between form 1 and casing 8, the unused portions thereof lying in folds, as at 13. In this embodiment the tapes are doubled and extend from one wall of covering 12, to which in this instance they are secured, through openings 6 and 7 and through openings 14, provided in the opposite side of said covering, and are adapted to have their operative length shortened or lengthened according to the transverse dimensions desired to be secured, the connected areas being held in fixed relation by knots 15 tied in said tapes, which engage with the walls of openings 14.

The dress-form when in use is mounted upon a sectional standard 16, comprised by a plurality of detachable sections capable of adjustment and held in adjusted position by means of set-screws 17, enabling the same to be maintained at any desired height. Standard 16 is mounted detachably upon a plate 18, let into the upper wall of a hollow base 19, the upper surface of said plate coming flush with the upper surface of said hollow base. By means of this construction the dress-form when deflated and the several parts of the sectional standard may be disconnected one from another and stored or

packed within the hollow base, as shown in Fig. 5.

In using the dress-form a casing conforming to the measurements of the person to be fitted is first placed upon the deflated form and tapes 9 connected thereto. The several tapes 11 are then passed through openings 6 and 7 of form 1 and connected to the eyes or other devices upon the opposite wall of the casing. Form 1 is then inflated until the tension of the outer casing is sufficient to cause the form to be retained substantially rigid. The dress-form in this condition is ready for use, and a garment to be made may be fitted thereon without the presence of the person for whom the garment is intended. Should the pressure of inflation tend to cause certain parts or areas of the casing to be expanded or distended, tapes 11 will retain the same in their proper relation, and by reason of the adjustable character of said tapes, as shown in the embodiment illustrated in Fig. 4, the transverse dimensions of the form may be changed at will by simply drawing them through the openings provided in covering 12 and tying the free ends thereof outside openings 14.

While the form is well adapted to attain the objects of my invention without the covering shown in Fig. 4, this covering is useful in protecting the inflated form, and its presence renders less likely the puncturing of said form when a garment is being fitted or pinned upon the outer casing. It will accordingly be seen that I have provided a construction well adapted to attain the objects of my invention and one which may be made to conform exactly to the diametrical measurements of the several portions of a human figure. The form, being collapsible, may be readily stored in small compass when not in use, and by reason of the adjustable character of the standard upon which it is mounted the length or hang of skirts may be readily determined.

While the form herein illustrated is designed particularly for fitting of women's garments, it will be apparent that the same may be used in the fitting of garments for men, and in any case it will be understood that when an individual casing has once been constructed it is possible by its co-operation with the inflatable form to secure the precise dimensions of the garment to be fitted without the presence of the person for whom the garment is intended.

Another important use to which my invention may be put is in surgical operations for correcting spinal curvatures or other defects of the spine, as in cases where it is desired to construct plaster casts. Heretofore in such operations it has been necessary to keep the person being operated upon suspended by the neck for a long period of time to enable the surgeons to construct the cast.

By my invention, however, it is only necessary to suspend the person for a time sufficient to allow one of the inelastic casings to be fitted to the body, after which this casing 5 may be inflated, as described, and a plaster cast constructed thereon.

As many changes could be made in the above construction and many apparently widely different embodiments of my invention could be made without departing from the scope thereof, I intend that all matter contained in the above description or shown in the accompanying drawings shall be interpreted as illustrative and not in a limiting 15 sense.

I desire it also to be understood that the language used in the following claims is intended to cover all of the generic and specific features of the invention herein described 20 and all statements of the scope of the invention which as a matter of language might be said to fall therebetween.

Having described my invention, what I claim as new, and desire to secure by Letters 25 Patent, is—

1. A dress-form comprising a casing of substantially non-elastic material mounted upon a support, an inflatable form located within said casing and furnished with means whereby the same may be inflated, and a flexible member extending from one wall of said casing through an opening in said form and having a detachable connection with the opposite wall of said casing.

35 2. A dress-form comprising an inflatable form mounted upon a fixed support and having an opening extending therethrough, a casing of inelastic material within which said form is inclosed, and a cord or tape which extends through the opening in said form and provides a detachable tying means between the opposite walls of said casing.

3. A dress-form comprising a collapsible form member, and a relatively inelastic form member superposed thereon, both of said form members being mounted upon a support, said inelastic form member being partially retained in predetermined shape as to diametrical measurements by a cord or tape 45 extending through the same and connected with opposite walls thereof.

4. A dress-form comprising a collapsible form member secured to a fixed support, a substantially inelastic form member superposed upon said form member and detachably secured to said support, and a cord or tape secured to one wall of said inelastic form member and having a detachable connection with the opposite wall thereof, said 55 cord or tape operating partially to retain said dress-form in predetermined shape as to diametrical measurements.

5. A dress-form comprising an inflatable form member secured upon a fixed support, 60 a substantially inelastic form member super-

posed upon said form member and detachably secured to said support, and a plurality of cords or tapes secured to one wall of said inelastic form member and having detachable connections with the opposite wall thereof, said cords or tapes operating partially to retain said dress-form in predetermined shape.

6. A dress-form comprising an inflatable form member mounted upon a fixed support, 75 a form member of substantially inelastic material superposed thereon and detachably connected with said support, said inflatable form member being provided with a plurality of openings extending therethrough, 80 and a plurality of flexible members extending through said openings and connecting opposite walls of said inelastic form member.

7. A dress-form comprising a collapsible casing formed of substantially inelastic material secured to a rigid base, an inflatable bag located within said casing and furnished with means whereby the same may be inflated, and a plurality of flexible members attached to one wall of said inelastic casing, 85 extending through a plurality of openings in said bag and connected to the opposite wall of said casing, whereby said casing is partially retained in shape.

8. A dress-form comprising a casing-form 95 of inelastic material having flexible members whereby the same may be detachably connected to a support, an inflatable form for said casing, said form being provided with a plurality of openings, and flexible bands extending from one wall of said casing through said openings and connected with an opposite wall of said casing.

9. A dress-form comprising a collapsible outer casing of substantially non-elastic material secured to a support, an inner form provided with means whereby the same may be inflated, and adjustable means connecting together opposite walls of said casing whereby the diametrical dimensions of said casing 105 may be altered at will.

10. A dress-form comprising a collapsible outer casing of substantially non-elastic material mounted upon a support, an inner form provided with means whereby the same may be inflated, a flexible member for connecting together opposite walls of said casing, and means for changing the operative length of said flexible member whereby the diametrical dimensions of said casing may be 115 changed at will.

11. A dress-form comprising an inflatable form of elastic material secured upon a support, a casing of relatively inelastic material inclosing said form, the opposite walls of said casing being tied by flexible connecting means, and means for shortening or lengthening said flexible connecting means to alter the diametrical dimensions of said casing.

12. A dress-form comprising a collapsible 30

- form member secured to a fixed support, a substantially inelastic form member superposed upon said first-mentioned form member and detachably secured to said support,
 5 a cord or tape secured to one wall of said inelastic member and having a detachable connection with the opposite wall thereof, said cord or tape operating partially to retain said dress-form in shape, and means for adjusting
 10 the effective length of said cord or tape whereby the diametrical dimensions of said inelastic member may be changed at will.
 13. A dress-form comprising a casing formed of substantially non-elastic material
 15 mounted upon a support, an inflatable lining for said casing, and means extending transversely through said casing and through an opening in said lining adapted to form an adjustable connection between the opposite
 20 walls of said casing whereby the shape thereof may be changed at will when the lining is in an inflated condition.
 14. A dress-form comprising a casing formed of substantially non-elastic material
 25 mounted upon a support, an inflatable lining for said casing, and a plurality of cords or tapes attached to a wall of said casing which extend transversely through a plurality of openings in said lining and through an opening in the opposite wall of said casing, said cords or tapes being adapted to have their effective length lengthened or shortened whereby the form of said casing may be changed at will.

15. A pneumatic dress-form comprising, in combination, a casing adapted to be held in a distended condition by pneumatic pressure, means extending transversely therethrough and connecting certain parts or areas thereof adapted partially to maintain the same in predetermined shape, and means whereby the length of said connecting means may be changed at will to alter the diametrical dimensions of said casing.

16. A pneumatic dress-form comprising, in combination, a substantially inelastic casing adapted to be held in a distended condition by pneumatic pressure, and a plurality of bands or tapes extending transversely therethrough and connecting certain parts or areas thereof adapted partially to maintain the same in predetermined shape.

17. A pneumatic dress-form comprising, in combination, a substantially inelastic casing adapted to be inflated and held in distended condition by pneumatic pressure, and a flexible member extending transversely through said form and connecting said parts or areas thereof adapted partially to maintain the same in predetermined shape, said flexible member having a detachable connection with one of the walls of said form.

In testimony whereof I affix my signature in the presence of two witnesses.

PRUDENCE ANN SMITH.
